UNITED STATES PATENT OFFICE.

CHARLES D. GOLDEN, OF CHICAGO, ILLINOIS.

DESIGN FOR A CLOCK-CASE.

SPECIFICATION forming part of Design No. 26,671, dated February 23, 1897.

Application filed January 18, 1897. Serial No. 619,494. Term of patent 3 $\frac{1}{2}$ years.

To all whom it may concern:

Be it known that I, CHARLES D. GOLDEN, a citizen of the United States, residing at Chicago, in the county of Cook and State of Illinois, have invented and produced a new and original Design for Clock-Cases, of which the following is a specification, reference being had to the accompanying drawing, embodied in a single figure, showing a front elevation in relief of a clock-case illustrating my design.

The principal feature of my design consists of the figure of a woman symbolizing America supporting a shield, with her left hand bearing stars and bars, the central feature of which is a clock-face.

Referring to the drawing, *a* represents the figure of a woman in a sitting posture wearing the usual drapery, with the folds of a flag over her left arm and across her lap. Her hair hangs loosely over her shoulders, a lib-

erty-cap surmounts her head, and an olive-wreath is grasped in her right hand. With her left hand she supports a union shield *a'* bearing the stars and bars and having a clock-face as its central feature. At the base of the shield are two crossed sheaves of wheat. At the right of the figure in the foreground are represented a plow, an anchor, an anvil, a hammer, and a gear-wheel, symbolizing agriculture, commerce, and mechanics. 30

I claim—

The design for a clock-case, substantially as shown and described.

In testimony whereof I have signed this specification, in the presence of two subscribing witnesses, this 23d day of December, 1896.

CHAS. D. GOLDEN.
